UNITED STATES PATENT OFFICE.

FREDERICK C. JULYAN, OF CLEVELAND, OHIO.

PAPER-FOLDING MACHINE.

1,196,697.

Specification of Letters Patent. Patented Aug. 29, 1916.

Application filed January 23, 1913. Serial No. 743,796.

To all whom it may concern:

Be it known that I, FREDERICK C. JULYAN, a citizen of the United States, and a resident of Cleveland, county of Cuyahoga, and 5 State of Ohio, have invented a new and useful Improvement in Paper-Folding Machines, of which the following is a specification, the principle of the invention being herein explained and the best mode in which 10 I have contemplated applying that principle, so as to distinguish it from other inventions.

The subject of the present invention is a machine adapted for folding paper, for 15 office use in folding up ready for mailing a number of sheets of equal size which must be picked up and folded singly. Machines for accomplishing this end are already known, but difficulty has been met with in 20 these machines in that they are complicated in operation and construction, and hence are not capable of continuously perfect operation. Furthermore, some of these machines are 25 open to the objection that they do not pick up and fold single sheets, but in many cases fold up together two, or possibly more, sheets, in which case the folded sheets must be carefully looked over and those which are folded together must be separated.

30 It is the object of the present invention to provide a machine which is simple and compact in construction and is capable of continuously perfect operation.

To the accomplishment of the foregoing 35 and related ends said invention, then, consists of the means hereinafter fully described and particularly pointed out in the claims.

The annexed drawings and the following 40 description set forth in detail certain mechanism embodying the invention, such disclosed means constituting, however, but one of various mechanical forms in which the principle of the invention may be used.

In said annexed drawings: Figure 1 is an 45 end elevation of the machine; Fig. 2 is a side elevation showing the folding mechanism in its initial position; Fig. 3 is a similar side elevation, but showing a part only of the machine and showing the folding 50 mechanism in its operating position; Fig. 4 is a similar side elevation partially in section showing the folding mechanism in its raised position; Fig. 5 is a similar view

showing the folding mechanism in the position assumed after the folding operation 55 proper has been completed; Fig. 8 is an elevation of the opposite side of the machine to that shown in Figs. 2 to 5 inclusive; and Figs. 6 and 7 are vertical sections showing details of construction, and are 60 taken on the lines 6—6 and 7—7 respectively in Fig. 1.

The operating mechanism may be mounted upon any suitable base or frame, the one here shown consisting of two vertically parallel sides 1 which are spaced from each other and are connected by cross bars or rods 2. Each side member 1 of the frame is roughly triangular in form, thus providing two upwardly extending portions which 70 are adapted to support certain of the operating mechanism which will be subsequently described in detail. The general features of the construction of the base are not of prime importance excepting so far as they 75 coöperate with the operating mechanism, such coöperating parts being described in connection with the operating mechanism at the proper points in the description.

A suitable magazine for receiving a plurality of loose sheets is provided, such magazine consisting of an open tray having a roughly rectangular bottom 4 and upwardly extending arms 5, the magazine being removably and pivotally attached at one end 85 to a rod 3 which is mounted horizontally and transversely in the frame. This rod 3 may be removed from the frame, thus permitting the removal of the magazine which, while not an important point, yet increases the 90 efficiency of the machine since it permits the removal of an empty magazine and the substitution of a previously prepared and filled one. That end of the machine which is shown at the right in Fig. 2 will, for convenience of description, be henceforth referred to as the forward end, and such mechanism as extends from end to end of the frame, such as the magazine, will have its ends similarly designated. The rear end, 95 then, of the magazine rests upon a supporting cam 6 which is attached to a shaft 7 suitably mounted in the side members 1 of the base and extending therethrough, a ratchet wheel 8 being attached to the shaft 100 exteriorly of the base, such ratchet wheel

being rotated by means of a small operating pawl 9 pivotally attached to a second and larger pawl 10 which is pivotally mounted on the shaft 7. The smaller pawl 9 is held in a position to normally restrain rotation of said ratchet wheel except in a direction to raise the magazine by means of a spring 11 attached to the small pawl 9 and the larger pawl 10. A spring latch 12 is also provided, being mounted on the base and adapted to engage the ratchet wheel to further prevent rotation of the same except in an operating direction, the function of the smaller pawl being rather to rotate the ratchet wheel upon actuation of the larger pawl than to restrain the same from rotation, although such is the effect of its engagement with the wheel. A spring 65 is provided for returning the pawl 10 to normal position. The advantage of the adjustable support for the rear end of the magazine is that as the paper held in the magazine is folded up the surface of the pile of loose sheets will be lowered, and unless it were made possible to raise this surface by some such means as the cam adjustment of the magazine, it would be probable that the operation of the folding mechanism would be rendered inefficient.

Intermediate the ends of the magazine I provide means for causing a slight bulge in the pile of loose sheets held in the magazine. Such means comprise a plate 13 provided with two downwardly extending ears 14 loosely entering apertures in the bottom of the magazine, the other side or edge of the plate resting upon screws 15 adjustably mounted in the bottom of the magazine and extending above the surface of the same. Adjustment of such screws will position such other edge of the plate at various heights above the bottom of the magazine, thus causing the bulge in the paper which is desired at some point, the exact point being determined by the operation of the folding mechanism, as will be better understood after the description of such mechanism.

The folding mechanism is borne partially on the base. Furthermore, the folding mechanism is either operated directly from the carriage or indirectly from the same through suitable shaftings and gears. Such carriage, then, consists of an open rectangular frame consisting of side bars 16 disposed externally of the sides of the base and connected by cross bars 17. The forward end of the carriage is pivotally connected to two connected supporting members 18 which are pivotally attached to the sides 1 of the frame. It will be noticed that both the magazine and the carriage are supported at their forward ends about parallel transverse axes which are adjacent to one another. Attention is called to this feature as it is an

important advantage in the operation of the magazine, as will be brought out in the following paragraphs.

Means for adjusting the pressure of the rear end of the carriage upon the surface of the pile of paper in the magazine are provided, such adjusting means preferably consisting of a threaded rod 19 extending rearwardly from the rear end of the carriage and bearing, adjustably mounted thereon, a weight 20. The purpose of such adjustable weight is to adapt the pressure of the rear end of the carriage which rests on the paper to the quality of the paper which is to be folded, as it will be understood that the coarser and stiffer the paper the greater will be the pressure which will be required to properly pick up and fold the same.

Rotatably mounted in the rear end of the carriage is a friction roller 21 which is provided with a gear 22 normally restrained from rotation, except in one direction, by means of a spring latch 23. A second roller 24 is provided with extending axles 25 which are slidably mounted in parallel upwardly extending slots 26 formed in the sides of the frame. A gear 27 is disposed upon the roller 24 and is adapted to engage the gear 22 on the friction roller 21 upon movement of such last named roller into substantial contact with the second roller 24. A guide in the form of a wire 28 is attached to the rear end of the carriage and extends forwardly of the friction roller 21, the main portion of the wire lying above and between the two rollers. The purpose of such guide is to prevent the second roller 24 from impeding the raising of the paper after the same is once folded. Disposed parallel with such slots 26 is a rack 29 normally engaged by the gear 27 on the roller 24. The slots 26 and the rack 29 form portions of circles having for their center the axis of the carriage when the latter is moved into its limiting forward position, (see Fig. 3).

The paper folding means which have just been described, and which consist briefly of the two rollers, are adapted to raise and fold a single paper and to convey the same to receiving means which may be of any suitable form, but are here shown as consisting of a plurality of rollers 30, 31 and 32, the roller 31 being preferably a friction roller. Such rollers are mounted upon suitable shafts which are journaled in the sides of the frame, the rollers being parallel to the lower rollers 24 and 21. The paper upon being raised is received between the rollers 30 and 31, the friction roller 31 being operated to draw the paper up between such rollers into a pocket or envelop 33. The roller 32 takes no part in such operation but is designed to coöperate with the roller 31 in removing the paper from the envelop and again folding the same. The action of these rollers in

again folding the paper and removing it from the envelop will be described at length hereinafter, and it is only necessary to say at this point that the paper will be removed from the pocket between the rollers 31 and 32 onto the stacking mechanism which consists of two guides 34 suitably mounted upon the frame, an adjustable back 35 slidably mounted upon such guides, and an oscillating shaft 36 oscillatorily mounted in the frame and provided with extending fingers 37 which are adapted to receive the folded paper and to force the same against the back 35 or against the pile of papers already held against such back. Attached to the shaft 36 is a link 38 which is slidably and pivotally attached to a pivotally mounted bar 39, such sliding and pivotal attachment being by means of a lug 40 attached to the link and held in an open slot 41 in the end of such bar 39. The other end of the bar is adapted to be contacted by the side of the carriage upon the operation of the latter, thus oscillating the bar and moving the fingers as has been described. A spring 42 is provided for returning the link and bar to their normal positions.

The carriage is adapted to be reciprocated longitudinally across the magazine moving from the position shown in Fig. 2, first forwardly and then returning to its initial position. Resilient means in the form of a coiled spring 43 attached to a cross bar 2 of the base and to the forward end of the carriage are provided for moving the carriage forwardly. Mounted upon a bracket 66 attached to one side of the frame is a gear 44 to which there is adjustably attached a cam 45 in contact with and operating a contact member 46 having a vertical contact face, and being mounted to slide horizontally upon a pin 47 mounted in such bracket. The gear 44 is rotatably mounted upon this pin 47. Such contact member is attached by means of a rod 48 to the forward end of the carriage, and it will be seen that rotation of such cam will limit the action of the spring in moving the carriage forwardly and will also positively return the carriage to its initial position. Adjustment of such cam will increase or decrease, as desired, the length of stroke of the carriage and will also determine the forward position to which the carriage can be moved by means of the spring. Attached to the other side of the gear 44 is a second cam 49 which is adapted to engage the under side of the sides 16 of the carriage and to lift the rear end of the carriage, thus tilting the same about its axis. It will be understood that the gear 44 is in reality a stub shaft for operating the two cams, and such shaft may be substituted for the gear if it is desired to position the latter at some other point. The

relation between the two cams will be such that the lifting cam will not operate to tilt the carriage until the reciprocating cam has permitted the spring to move the carriage to such a position that the friction roller 70 and the second roller 24 are in substantial contact with the folded sheet between, the gears 22 and 27 on such rollers being at this time in mesh with one another.

Pivotaly mounted in the sides of the base 75 is a shaft 50 which extends through one side of the base and is provided with a hand wheel 51 for convenient rotation. Such shaft bears a gear 52 which meshes with and drives the gear 44 which operates 80 the two cams. The friction roller 31 in the upper portion of the frame is also provided with an extending portion which bears a gear 53 driven by such gear 52 on shaft 50. The shafts 30 and 32 bear gears 54 and 55 85 respectively, each of which meshes with a second gear 67 on the friction roller 31, such rollers 30 and 32 being operated therefore from the friction roller 31. Mounted laterally upon the rear end of the carriage 90 is a lug 68 which is adapted to engage and operate the pawl 10 which rotates the adjusting cam for the magazine and raises the same. So long as the paper in the magazine is at a predetermined level, which 95 is when it permits the folding mechanism to properly operate, the lug 68 will not engage the pawl 10. Upon the folding of a number of the sheets the surface of the pile will be lowered and the lug 68 will then 100 engage the pawl 10 and operate the mechanism upon each movement of the carriage until the rear end of the magazine has been raised to such a point that the folding mechanism may operate properly, at which 105 point the rear end of the carriage will be above the pawl 10, and further adjustment of the magazine will cease.

The operation of the mechanism will be as follows: In the initial position of the 110 folding means, which is that shown in Fig. 2, the friction roller and the second roller 24 are both resting upon the surface of the papers in the magazine. Rotation of the hand wheel in a clockwise direction when 115 looking at the same from the viewpoint taken in Fig. 2 will permit the spring 43 to move the carriage forwardly across the magazine, thus drawing the friction roller 21 across the uppermost sheet of paper 120 which is at this point slightly bulged by the action of the plate 13 on the bottom of the magazine. The tendency of the friction roller will be to rotate in a clockwise direction upon such movement, but this tendency 125 is prevented by the latch 23, the surface of the roller, which is preferably rubber, thus picking up or bulging the uppermost sheet of paper, forcing the same against the second roller 24 into the position shown in 130

Fig. 3. The paper is thus folded, and further rotation of the hand wheel brings the lifting cam 49 into engagement with the lower side of the sides 16 of the carriage, thus raising the same into the position shown in Fig. 4. Such action of the carriage would in itself raise the folded paper away from the magazine to some extent, but as the gears 22 and 27 are in engagement, the latter gear engaging the rack 29 which is stationary, the rollers 21 and 24 are both operated upon such raising of the carriage, and the paper is thus moved upwardly between the rollers into engagement with the rollers 30 and 31. Continued rotation of the hand wheel permits the rear end of the carriage to return to its initial position, the action of the cam 45 spacing the rollers 21 and 24 as soon as the rear end of the carriage begins to descend, thus releasing the paper and preventing the same from being hindered in its further upward movement between the rollers 30 and 31. The guide 28 causes the paper to be drawn away from the roller 24 as the rear end of the carriage descends, so that the lower edge of the folded sheet is entirely clear from the roller 24 when the latter is brought to rest in its initial position.

As the rollers 30 and 31 are being continuously operated from the shaft 50 during such operation of the folding mechanism, the folded sheet is drawn up into the pocket 33, and as the folded edge of the paper engages the top of the pocket, the friction roller 31 continues to draw the paper upward, the paper thus bulging at its central portion in the space between the friction roller 31 and the coöperating roller 32. These two rollers operate to thus again fold the paper and to convey the same onto the fingers 37 of the stacking mechanism. An arm 58 is attached to the pocket and is provided for the purpose of retaining the stacked papers in such position, as will be readily understood from an inspection of Fig. 2.

The importance of having the magazine and the carriage pivoted about adjacent parallel axes will now be understood. As the magazine is adjusted it will be tilted more and more forwardly, and unless the carriage be so mounted that the friction roller 21 is adapted to be moved, upon the first movement of the carriage, in a direction substantially parallel with the surface of the paper, it is impossible for the same to efficiently operate to pick up a single paper. The features of the invention to which particular attention is called are the means for raising and folding a single paper and it will be understood that other suitable means besides those here shown may be provided for receiving and stacking the folded papers. While it will be seen that the folding

mechanism has been so constructed and combined in the present mechanism to efficiently coöperate with the particular means shown for receiving and stacking the papers, yet it will be understood that such last named feature of the mechanism will be controlled in its construction and operation to a large extent by the use to which the machine is to be put. Thus, when handling a certain class of papers it is desirable to fold the same, once centrally and then transversely, and in such a case other means than those here shown would necessarily have to be used. The present invention therefore resides in the mechanism for picking up and folding the papers and in the coöperative combination between such mechanism and the means for receiving and further handling such folded paper.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a machine of the character described, the combination of a magazine adapted to receive papers; a movably mounted carriage; means adapted to move said carriage across said magazine and to raise said carriage from said magazine; and means operated by said carriage and adapted to pick up and fold a single paper at a time.

2. In a machine of the character described, the combination of a magazine adapted to receive papers; a reciprocably mounted carriage; means adapted to move said carriage across said magazine and to raise said carriage from said magazine; a friction roller mounted on said carriage and adapted to pick up a single paper; and a second roller adapted to coöperate with said friction roller to fold such paper.

3. In a machine of the character described, the combination of a magazine adapted to receive papers; a reciprocably mounted carriage, said carriage being also adapted to tilt; means adapted to move said carriage across said magazine and to tilt said carriage, thereby raising the same from said magazine; a friction roller mounted on said carriage and adapted to pick up a single paper; and a second roller adapted to coöperate with said friction roller to fold such paper.

4. In a machine of the character described, the combination of a magazine adapted to receive papers; a reciprocably mounted carriage, said carriage being also pivotally mounted about an axis disposed transversely to the direction of movement of said carriage; means adapted to move said carriage

and to tilt the same about such transverse axis, thereby raising said carriage from said magazine; a friction roller carried by said carriage and adapted to pick up a single paper; and a second roller adapted to coöperate with said friction roller to fold such paper.

5. In a machine of the character described, the combination of a magazine adapted to receive papers; a reciprocably mounted carriage, said carriage being also pivotally mounted about an axis disposed transversely to the direction of movement of said carriage; means adapted to move said carriage and to tilt the same about such transverse axis, thereby raising said carriage from said magazine; a friction roller carried by said carriage and adapted, upon movement of the same across said magazine, to pick up a single paper, and a second roller movably mounted and adapted to coöperate with said friction roller to fold and raise a single paper from said magazine.

6. In a machine of the character described, the combination of a base; a magazine substantially horizontally mounted thereon and adapted to receive a plurality of loose papers; a horizontally movable carriage on said base, said carriage being also pivotally mounted about an axis disposed transversely with respect to the direction of horizontal movement of said carriage; means adapted to move said carriage across said magazine; other means adapted to tilt said carriage about such transverse axis; a friction roller mounted on said carriage; and a second roller adapted to coöperate with said friction roller to fold and raise a single paper from said magazine; said base being provided at either side of said magazine with parallel upwardly extending slots, said second roller being slidably mounted in said slots and being adapted to be raised by the tilting movement of said carriage.

45 7. In a machine of the character described, the combination of a base; a magazine substantially horizontally mounted thereon and adapted to receive a plurality of loose papers; a horizontally movable carriage on said base said carriage being also pivotally mounted about an axis disposed transversely with respect to the direction of horizontal movement of said carriage; means adapted to move said carriage across said magazine; other means adapted to tilt said carriage about such axis; a friction roller mounted on said carriage and adapted to pick up a single paper upon movement of said carriage; a second roller provided with extending axles, said second roller being adapted to coöperate with said friction roller to fold and raise a single paper from said magazine; said base being provided with parallel slots extending upwardly from the lowest level of said carriage; said second

roller being slidably mounted in such slots, such axles extending through the same into the path of movement of said carriage, whereby tilting of said carriage raises said second roller.

70 8. In a machine of the character described, the combination of a base; a magazine substantially horizontally mounted thereon and adapted to receive a plurality of loose papers; a horizontally movable carriage on said base said carriage being also pivotally mounted about an axis disposed transversely with respect to the direction of horizontal movement of said carriage; means adapted to move said carriage across said magazine; other means adapted to tilt said carriage about such axis; a friction roller mounted on said carriage and adapted to pick up a single paper upon movement of said carriage; a second roller provided with extending axles, 85 said second roller being adapted to coöperate with said friction roller to fold and raise a single paper from said magazine; said base being provided with parallel slots extending upwardly from the lowest level of said carriage; said second roller being slidably mounted in such slots, such axles extending through the same into the path of movement of said carriage, whereby tilting of said carriage raises said second roller; and means 90 adapted to rotate said contacting rollers during the tilting movement of said carriage thereby raising said paper from between the same.

9. In a machine of the character described, 100 the combination of a base; a magazine substantially horizontally mounted thereon and adapted to receive a plurality of loose papers; a horizontally movable carriage on said base said carriage being also pivotally mounted about an axis disposed transversely with respect to the direction of horizontal movement of said carriage; means adapted to move said carriage across said magazine; other means adapted to tilt said carriage 105 about such axis; a friction roller mounted on said carriage and adapted to pick up a single paper upon movement of said carriage; a second roller provided with extending axles, said second roller being adapted to 110 coöperate with said friction roller to fold and raise a single paper from said magazine; said base being provided with parallel slots extending upwardly from the lowest level of said carriage; said second roller being slidably mounted in such slots, such axles extending through the same into the path of movement of said carriage, whereby tilting of said carriage raises said second roller; a rack attached to said base, said rack being parallel with said slots; and similarly disposed complementary gears carried on said rollers, one of said gears being adapted to engage said rack upon upward movement 115 of said rollers, whereby said rollers are ro- 120 125 130

tated and such paper therebetween raised therefrom.

10. In a machine of the character described, the combination of a base; a magazine substantially horizontally mounted thereon and adapted to receive a plurality of loose papers; a horizontally movable carriage on said base said carriage being also pivotally mounted about an axis disposed transversely with respect to the direction of horizontal movement of said carriage; means adapted to move said carriage across said magazine; other means adapted to tilt said carriage about such axis; a friction roller mounted on said carriage and adapted to pick up a single paper upon movement of said carriage; a second roller provided with extending axles, said second roller being adapted to coöperate with said friction roller to fold and raise a single paper from said magazine; said base being provided with parallel slots extending upwardly from the lowest level of said carriage; said second roller being slidably mounted in such slots, such axles extending through the same into the path of movement of said carriage, whereby tilting of said carriage raises said second roller; a rack attached to said base, said rack being parallel with said slots; similarly disposed complementary gears carried on said rollers, one of said gears being adapted to engage said rack upon upward movement of said rollers, whereby said rollers are rotated and such paper therebetween raised therefrom; and means adapted to receive such paper from said rollers.
11. In a machine of the character described, the combination of a base; a magazine substantially horizontally mounted thereon and adapted to receive a plurality of loose papers; a horizontally movable carriage on said base said carriage being also pivotally mounted about an axis disposed transversely with respect to the direction of horizontal movement of said carriage; means adapted to move said carriage across said magazine; other means adapted to tilt said carriage about such axis; a friction roller mounted on said carriage and adapted to pick up a single paper upon movement of said carriage; a second roller provided with extending axles, said second roller being adapted to coöperate with said friction roller to fold and raise a single paper from said magazine; said base being provided with parallel slots extending upwardly from the lowest level of said carriage; said second roller being slidably mounted in such slots, such axles extending through the same into the path of movement of said carriage, whereby tilting of said carriage raises said second roller; a rack attached to said base, said rack being parallel with said slots; similarly disposed complementary gears carried on said rollers, one of said gears being

adapted to engage said rack upon upward movement of said rollers, whereby said rollers are rotated and such paper therebetween raised therefrom; and means adapted to receive such paper from said rollers, said means including other rollers mounted parallel to said friction and said second rollers.

12. In a machine of the character described, the combination of a base; a magazine substantially horizontally mounted thereon and adapted to receive a plurality of loose papers; a support pivotally attached to said base; a carriage pivotally attached at one end to said support and normally resting on said magazine at the other end; rollers operated by said carriage upon movement of the same, said rollers being adapted to pick up, fold and raise a single paper; and means adapted to move said carriage across said magazine, then raise said carriage and return the same to its original position.

13. In a machine of the character described, the combination of a base; a magazine substantially horizontally mounted thereon and adapted to receive a plurality of loose papers; a support pivotally attached to said base; a carriage pivotally attached at one end to said support and normally resting on said magazine at the other end; rollers operated by said carriage upon movement of the same, said rollers being adapted to pick up, fold and raise a single paper; resilient means attached to said base and said carriage and adapted to move said carriage across said magazine; and other means adapted to raise and return said carriage to its original position.

14. In a machine of the character described, the combination of a base; a magazine substantially horizontally mounted thereon and adapted to receive a plurality of loose papers; a support pivotally attached to said base; a carriage pivotally attached at one end to said support and normally resting on said magazine at the other end; rollers operated by said carriage upon movement of the same, said rollers being adapted to pick up, fold and raise a single paper; resilient means attached to said base and said carriage and adapted to move said carriage across said magazine; a rotatable shaft mounted in said base; and cam members attached to said shaft and adapted to raise and return to its original position said carriage.

15. In a machine of the character described, the combination of a base; a magazine substantially horizontally mounted thereon and adapted to receive a plurality of loose papers; a support pivotally attached to said base; a carriage pivotally attached at one end to said support and normally resting on said magazine at the other

end; rollers operated by said carriage upon movement of the same, said rollers being adapted to pick up, fold and raise a single paper; resilient means attached to said base 5 and said carriage and adapted to move said carriage across said magazine in one direction; a rotatable shaft mounted in said base; and cam members attached to said shaft and adapted to raise said carriage, and then to 10 return the same to its original position on said magazine.

16. In a machine of the character described, the combination of a base; a magazine substantially horizontally mounted 15 thereon and adapted to receive a plurality of loose papers; a support pivotally attached to said base; a carriage pivotally attached at one end to said support and normally resting on said magazine at the other 20 end; rollers operated by said carriage upon movement of the same, said rollers being adapted to pick up, fold and raise a single paper; resilient means attached to said base and said carriage and adapted to move said 25 carriage across said magazine in one direction; a rotatable shaft mounted in said base; a plate cam attached to said shaft and adapted to raise said carriage; and other cam means attached to said shaft and adapted to return said carriage to its original 30 position.

17. In a machine of the character described, the combination of a base; a magazine substantially horizontally mounted 35 thereon and adapted to receive a plurality of loose papers; a support pivotally attached to said base; a carriage pivotally attached at one end to said support and normally resting on said magazine at the other 40 end; rollers operated by said carriage upon movement of the same, said rollers being adapted to pick up, fold and raise a single paper; resilient means attached to said base and said carriage and adapted to move said 45 carriage across said magazine in one direction; a rotatable shaft mounted in said base; a plate cam attached to said shaft and adapted to raise said carriage; a vertically disposed contact member attached to said 50 carriage; and a second plate cam attached to said shaft and adapted to actuate said contact member to return said carriage to its original position.

18. In a machine of the character described, the combination of a base; a magazine substantially horizontally mounted thereon and adapted to receive a plurality of loose papers; a support pivotally attached to said base; a carriage pivotally attached 55 at one end to said support and normally resting on said magazine at the other end; rollers operated by said carriage upon movement of the same, said rollers being adapted to pick up, fold and raise a single paper; resilient means attached to said base and

said carriage and adapted to move said carriage across said magazine in one direction; a rotatable shaft mounted in said base; a plate cam attached to said shaft and adapted to raise said carriage; a horizontal pin 70 mounted on said base; a bar pivotally attached to the forward end of said carriage and slidably mounted on said pin, said bar having a vertical contact surface at its rear end; and a second plate cam attached to said shaft and adapted to engage such contact surface on said bar and thereby return said carriage to its original position.

19. In a machine of the character described, the combination of a base; a magazine 75 removably mounted substantially horizontally thereon and adapted to receive papers; a movable carriage pivotally attached at one end to said base and normally resting on said magazine at the other end; means for moving said carriage across said magazine; and means operated by movement of said carriage and adapted to pick up and fold a single paper at a time.

20. In a machine of the character described, the combination of a base; a magazine 80 mounted on said base and adapted to receive papers; a carriage movably mounted on said base; a roller carried by said carriage and adapted to raise papers singly 85 from said magazine upon movement of said carriage; a second roller adapted to cooperate with said first-named roller to raise such single papers entirely free of said magazine; and a guide mounted on said carriage and adapted to hold such raised paper from engagement with said second roller upon return movement of said carriage.

21. In a machine of the character described, the combination of a base; a magazine 90 mounted on said base and adapted to receive papers; a support pivotally attached to one end of said base; a carriage pivotally attached to said support at one end, the 95 other end of said carriage normally resting on said magazine; a friction roller carried on said carriage; a vertically movable roller mounted in said base; a rack also mounted on said base parallel with the path of movement of said vertically movable roller; complementary gears similarly mounted on said rollers and adapted to engage upon horizontal movement of said carriage, said friction roller being adapted to pick up and fold a 100 paper against said second-named roller, said 105 gear on said second roller thereupon engaging said rack; and means adapted to raise said carriage, thereby raising said rollers and rotating the same, whereby such paper is raised between said rollers; other 110 means adapted to return said carriage to its normal position; means adapted to engage such paper in such raised position; and a pawl engaging said gear on said friction roller being adapted to restrain the same from rotation 115

during such return movement of said carriage.

22. In a machine of the character described, the combination of a base; a magazine mounted on said base and adapted to receive papers; a support pivotally attached to one end of said base; a carriage pivotally attached to said support at one end, the other end of said carriage normally resting

10 on said magazine; a friction roller carried on said carriage; a vertically movable roller mounted in said base; a rack also mounted on said base parallel with the path of movement of said vertically movable roller; complementary gears similarly mounted on said

15 rollers and adapted to engage upon horizontal movement of said carriage, said friction roller being adapted to pick up and fold a paper against said second-named roller, said

20 gear on said second roller thereupon engaging said rack; and means adapted to raise said carriage, thereby raising said rollers and rotating the same, whereby such paper is raised between said rollers; other

25 means adapted to return said carriage to its normal position; other rollers mounted in said base and adapted to engage therebetween said paper in such raised position and to further entirely raise the same free

30 from said magazine; a pawl engaging said gear on said friction roller to restrain the same from rotation during such return movement of said carriage; and a guide on

35 said carriage adapted to receive such raised paper and to prevent the same from engagement by said vertically movable roller upon the return movement of the same.

23. In a machine of the character described, the combination of a base; a magazine 40 mounted on said base and adapted to receive papers; a support pivotally attached to one end of said base; a carriage pivotally attached to said support at one end, the other

45 end of said carriage normally resting on said magazine; a friction roller carried on said carriage; a vertically movable roller mounted in said base; a rack also mounted on said base parallel with the path of movement of said vertically movable roller; complementary gears similarly mounted on said

50 rollers and adapted to engage upon horizontal movement of said carriage, said friction roller being adapted to pick up and fold a paper against said second-named roller, said gear on said second roller thereupon engaging said rack; and means adapted to raise said carriage, thereby raising said rollers and rotating the same, whereby such paper is raised between said rollers; other

55 means adapted to return said carriage to its normal position; other rollers mounted in said base and adapted to engage therebetween said paper in such raised position and to further entirely raise the same free from

60 said magazine; a pawl engaging said gear

65

on said friction roller to restrain the same from rotation during such return movement of said carriage; a guide on said carriage adapted to receive such raised paper and to prevent the same from engagement by 70 said vertically movable roller upon the return movement of the same; and other means adapted to simultaneously operate such carriage operating means and said other rollers.

24. In a machine of the character described, 75 the combination of a base; a magazine adapted to receive a plurality of loose papers, said magazine being pivotally attached at its forward end to one end of said base; means adjustably supporting the rear 80 end of said magazine; a carriage pivotally attached at its forward end to the same end of the base as is said magazine, the rear end of said carriage resting on such papers in said magazine; means adapted to move said 85 carriage across said magazine, whereby said carriage will always move in a direction substantially parallel to the surface of said magazine, as said magazine and said carriage have their adjacent ends pivotally attached to adjacent axes; and a friction roller carried by the rear end of said carriage and adapted to pick up a single paper upon movement of said carriage across said magazine.

25. In a machine of the character described, the combination of a base; a magazine mounted thereon and adapted to receive loose papers; a carriage pivotally mounted at one end on said base, the other 100 end of said carriage resting on such papers in said magazine; means attached to such other end of said carriage and adapted to pick up and fold a paper from said magazine upon movement of said carriage across 105 the same; and means adapted to vary the pressure of such other end of said carriage upon such papers.

26. In a machine of the character described, the combination of a base; a magazine mounted thereon and adapted to receive loose papers; a carriage pivotally mounted at one end on said base, the other end of said carriage resting on such papers in said magazine; means attached to such other end of said carriage and adapted to pick up and fold a paper from said magazine upon movement of said carriage across the same; and means adapted to vary the pressure of such other end of said carriage upon such papers, 115 said means including a threaded rod attached to said carriage at right angles to the pivotal axis of the same, and a weight adjustably mounted on such rod.

27. In a machine of the character described, the combination of a base; a magazine adapted to receive loose papers; a carriage movably attached to said base and provided with means adapted to pick up such 125 papers singly during such movement; means

adapted to move said carriage in one direction; and adjustable means adapted to limit such movement of said carriage by said first-named means and to return said carriage to its initial position. 15

28. In a machine of the character described, the combination of a base; a magazine adapted to receive loose papers; a carriage movably attached to said base and 10 provided with means adapted to pick up such papers singly during such movement; means adapted to move said carriage in one

direction; and an adjustably mounted cam member adapted to control and limit such movement of said carriage by said first-named means, to return said carriage to its initial position and to determine the same.

Signed by me, this 20th day of January, 1913.

FREDERICK C. JULYAN.

Attested by—

HORACE B. FAY,
MARY GLADWELL.
